UNITED STATES PATENT OFFICE.

JOHN F. RIDENOUR, OF HECTOR, OHIO.

SIGNAL-LIGHT.

SPECIFICATION forming part of Letters Patent No. 406,539, dated July 9, 1889.

Application filed March 18, 1889. Serial No. 303,713. (No model.)

To all whom it may concern:

Be it known that I, JOHN F. RIDENOUR, of Hector, in the county of Putnam and State of Ohio, have invented certain new and useful 5 Improvements in Signal-Lights; and I do hereby declare that the following is a full, clear, and exact description of the invention, which will enable others skilled in the art to which it appertains to make and use the same, 10 reference being had to the accompanying drawings, and to the letters of reference marked thereon, which form part of this specification.

My invention relates to an improvement in 15 signal-lights and devices for operating the same; and the invention consists in certain novel features of construction and combinations of parts, more fully described herein-after, and particularly pointed out in the 20 claims.

Referring to the accompanying drawings, Figure 1 is an elevation of a portion of a railroad-gate, showing the signal-light box with the door swung open and the lantern in position to be lowered. Fig. 2 is a view with 25 the door of the signal-light box closed, looking in the box from the rear. Fig. 3 is a top plan of the interior of the box when the door is open, with the top of the box removed.

30 The object of the invention is to provide a means for obviating the difficult and dangerous methods of placing lanterns on the tops of railroad-crossing gates, in sign-boxes, &c., at considerable distances above the ground. Heretofore, in order to place the lantern upon the upper end of the gate or at an altitude, a ladder or the like was rested against the gate, which the operator ascends; but as the gates are hinged and cannot be rigidly 35 secured in position it is unsafe to ascend a ladder placed against the same. This object is accomplished by the construction shown in the accompanying drawings, which construction is equally efficient and useful with semaphore-lanterns or any lanterns to be placed in an inclosure at a distance where it is difficult to climb. The lantern can be raised and lowered and moved horizontally in or out of a signal-light box. 40 In the drawings, the reference-letter *a* indicates a signal-light box or inclosure pro- 45 vided with any suitable number of glass panels, as shown, and with a horizontally- swinging hinged door *b*, preferably provided with a glass panel. A horizontal plate, arm, 55 or projection *c* extends inwardly from the inner side of the door near the upper inner edge of the same, and is provided with a flange by which the plate is secured to the door. A pulley *d* depends from the outer corner or 60 portion of the plate or arm, so that when the door is opened and the plate swings out with the same the pulley will be located above the opening between the inner face of the door and the edge of the box, and thereby 65 allow the lantern *e*, carried by the cord *f*, passing over said pulley, to pass out of the box and descend to the ground. The cord *f* extends from or near the ground up into the 70 inclosure through an opening in the bottom of the same and up the interior of the box to and over a pulley *g*, secured to the inside of the same near the top thereof, from whence horizontally to and over the pulley *d*, 75 from whence its free end hangs and carries 80 the lamp or lantern. It will thus be seen that when the door is open the plate or projection *c* and its supporting-pulley *d* are thrown out and the lamp is lowered to the ground for filling, &c., and the lamp is raised 85 by pulling down on the opposite end of the cord and drawing the same over pulleys *d* *g* until the lantern reaches a point above the bottom of the box and engages the pulley *d*, when the strain of the rope will tend to 90 shorten the horizontal portion of the cord and draw the pulleys *d* *g* together, and thereby swing the door closed, and the plate *c* will carry the lantern horizontally into the box as the door closes. The cord *f*, if desired, is 95 provided with a protecting-tube *f'*, as shown in Fig. 1. The door is opened from the ground by means of a wire or rod *h*, extending upwardly from within easy reach of the ground into the box or inclosure *a*. A horizontal rod 100 or connection *i* at its inner end is loosely secured at *i'* to the outer inner corner of the plate *c* opposite the hinged edge of the door, and from thence extends (when the door is closed) diagonally beneath the plate toward the opposite edge of the door, and the outer end of the horizontal connection *i* and the

upper end of the rod *h* are connected by the flexible connection *j* operating over the periphery of and supported by a vertical pulley *k*, located in the box opposite the free edge of the door and in a plane nearer the vertical plane of the door than the point of connection *i'* between said plate *c* and the inner end of connection *i*. Thus it will be readily seen that when the rod *h* is drawn down the rod *i* will be drawn longitudinally, and thereby swing open the door as the distance from point *i'* to the pivotal point of the door forms the power-arm of a lever to swing the door open. Said vertical pulley *k*, over which the flexible connection *j*' works, is carried by the upper end of a vertical latch-lever *m*, pivoted within its length in the box, so that its lower laterally-bent latch end *m'* can enter the staple or loop *n*, carried by the door, and thereby lock the same. The latch is provided with a spring *n'* to yieldingly hold it in locking position.

It will thus be seen that when the door is closed and it is desired to lower and remove the lantern the operator has merely to pull down on the rod or connection *h* and hook the loop on the end of the same over the projection *o*. This operation will open the door after the tension of the cord *j* on the pulley *k* has thrown out the lower end of the latch from engagement with the loop on the door and against the tension of the spring. The latch is held in this open position until the door is closed and the rod *h* released from the pin *o*, thereby relieving the lateral tension on the pulley *k* and allowing the latch to spring back to its normal locking position.

What I claim is—

1. A signal-light box adapted to be located a distance from the ground and provided with a hinged door, in combination with a rod or connection for opening said door from the ground, and a cord carrying the signal, by which the same can be raised or lowered, and connected with the door to close the same from the ground and swing the signal in or out of the box, substantially as described.

2. In combination, a signal-light box, a hinged door for the same, a cord loosely connected with the door and extending from the

same to or near the ground and carrying the signal, and by which the signal can be raised or lowered, and when raised to the door the same is closed, carrying the signal into the box, substantially as described.

55

3. In combination, a signal-light box, a hinged door for the same, an inwardly-extending plate or arm carried by the door, a cord connected with the plate or arm and adapted to carry the signal or lantern and extend to or near the ground and close the door, and thereby swing the lantern into the box, substantially as described.

4. A signal-light box provided with a hinged door, a latch for the door, a rod or connection secured to the door and extending down to or near the ground, and adapted to operate the latch to release the door and swing the same open, a cord connected with the door and adapted to carry the lantern and raise and lower the same and close the door and swing the lantern into the box, substantially as described.

65

5. A signal-light box provided with a hinged door, a cord to carry the light and raise and lower the same, and a plate or projection carried by the door, to which said cord is connected, and which is adapted to swing the lantern in and out of the box, substantially as described.

75

6. A signal-light box having a hinged door, an inwardly-extending plate or projection carried by the door, and provided with a pulley near its outer portion, and a pulley in the box, located opposite said pulley carried by the door, in combination with a rope or cable, said cable passing over said pulleys and depending from the same and adapted to extend to or near the ground, and a signal-light adapted to be inclosed in said box and carried by the portion of the cable depending from said plate, for the purpose set forth.

80

In testimony that I claim the foregoing as my own I affix my signature in presence of two witnesses.

JOHN F. RIDENOUR.
